VALVED CAP FOR CONTAINERS

Fred E. White, Nashville, Mich.

Application March 23, 1939, Serial No. 263,657

3 Claims. (Cl. 221—60)

The present invention relates to caps for containers of tooth paste and the like; and its object is to provide such a cap improved in various respects hereinafter appearing; and more particularly, to provide such a cap having a discharge opening and an improved valve for closing the same and improved means for operating the valve.

This and any other and more specific objects hereinafter appearing are attained by, and the invention finds preferable embodiment in, the illustrative structures particularly described in the body of this specification and illustrated by the body of this specification and illustrated by the accompanying drawing, in which:

15 Figure 1 is a side view of a valved cap for the vent of a container of tooth paste or the like, and a portion of such a container showing the cap applied thereto;

20 Figure 2 is a like view thereof but showing the same with the cap's valve opened by a tooth brush for applying the tooth paste thereto;

25 Figure 3 is a transverse sectional view of the same taken on line 3—3 of Figure 1;

Figure 4 is a bottom plan view of the cap;

25 Figure 5 is an axially sectional view of the cap and container taken on line 5—5 of Figures 3 and 4;

30 Figure 6 is a view, similar to Figure 5, with the valve in open position;

Figure 7 is another axially sectional view of the cap and container taken on line 7—7 of Figure 5;

Figure 8 is a side view of the cap and container showing a modified construction for connecting the cap with the container;

35 Figures 9, 10 and 11 are views of the cap and container showing another modified construction of the cap, Figure 9 being an axially sectional view, Figure 10 a transverse sectional view taken on line 10—10 of Figure 9, and Figure 11 being 40 another axially sectional view taken on line 11—11 of Figure 9.

As illustrated by this drawing a cap for a container (as a collapsible tube 1) for tooth paste or the like is detachably applied to the container's nipple 2 through which its vent 3 extends, in any suitable way as by screwing the threaded nipple into the cap's discharge opening 4 communicating with the vent, in the constructions illustrated by Figures 1—7 and 9—11, or by means 45 of the cap's bayonet slot 5 in which the nipple's pin or lug 6 engages as shown in Figure 8. Said cap has a body 7 in Figures 1—8 or 7¹ in Figures 9—11 having a slide bearing 8 or 8¹ comprising parallel grooves, in which the valve 9 or 9¹ is slideable to the position shown in Figures 5 and 9

wherein it closes the cap's opening 4 to prevent discharge of the contents of the container, and to the opposite position shown in Figure 6 wherein the cap's opening is opened. Means for operating the valve comprises a member 10 in Figures 1—8 or 10¹ in Figures 9—11, member 10 being turnable on a pintle 11 carried by the body 7 and operatively connected with the valve. In Figures 1—8 the bearing 8 extends in a direct line and the valve 9 is flat and is operatively connected with member 10 by mutually engaging parts as said member's arm 12 engaging in the valve's notch 13; while in Figures 9—11 the bearing 8¹ is arcuate, the valve 9¹ is correspondingly curved and the member 10¹ is operatively connected with this 18 valve integrally.

Suitable means for urging the valve 9 or 9¹ to normal closed position includes the spring 14 coiled around the pintle 11, one of its ends engaging the operating member 10 and its other end engaging the body 7 in Figures 1—8; or the spring 14¹ coiled around the pin 11¹ its ends engaging the operating member 10¹ and the plate 15 in Figures 9, 10 which plate may be removed by unscrewing its mounting screw 16 for assembling the valve 9¹ in the arcuate bearing 8¹.

The operating member 10 or 10¹ has an outer (under) surface 17, preferably curved as shown. The user holding the container in one hand and a tooth brush 18 in his other hand with the bristles thereof adjacent the mouth of the cross-sectionally rectangular portion 19 of the opening 4 of the cap, presses the bristles against the surface 17 of the operating member 10 or 10¹ as indicated in Figure 2 thus turning said operating member to the position in which it opens the valve to permit a ribbon 20 of the container's contents 21 to be spread on the bristles of the brush.

The invention being intended to be pointed out in the claims, is not to be limited to or by details of construction of any particular embodiment thereof illustrated by the drawings or hereinbefore described.

I claim:

1. A detachable cap for the vent of a tooth paste container or the like, having a body with a discharge opening communicating with the vent, a valve slideable on the body to and from operative position closing the opening and a member turnable on the body, operatively connected with the valve for sliding the same and having an outer surface adapted to be engaged, for turning said member to a position opening the valve, by a tooth brush or the like positioned adjacent the

mouth of the opening for receiving therefrom contents of the container, and means for urging the valve to normal closed position.

2. A detachable cap for the vent of a tooth paste container or the like, having a body with a discharge opening communicating with the vent, an arcuate slide bearing and a valve slidable in the bearing to and from operative position closing the opening and a member turnable on the body and operatively connected with the valve for sliding the same, and means for urging the valve to normal closed position.

3. A detachable cap for the vent of a tooth paste container or the like, having a body with a discharge opening communicating with the vent, an arcuate slide bearing having overhanging sides and a correspondingly arcuate valve in the bearing 5. slidable to and from operative position closing the opening the bearing having closing means at an end thereof removable for permitting the insertion of the valve endwise into the bearing, and means for urging the valve to normal closed 10 position.

FRED E. WHITE.
